UNITED STATES PATENT OFFICE.

ARTHUR J. MOXHAM, OF JOHNSTOWN, PENNSYLVANIA.

RAILROAD-TRACK.

SPECIFICATION forming part of Letters Patent No. 503,026, dated November 7, 1893

Application filed April 27, 1892. Serial No. 430,822. (No model.)

To all whom it may concern:

Be it known that I, ARTHUR J. MOXHAM, of Johnstown, in the county of Cambria and State of Pennsylvania, have invented a new and useful Improvement in the Art of Constructing Railroad-Tracks, which invention or improvement is fully set forth and illustrated in the following specification and accompanying drawings.

10 The object of this invention is to rigidly unite the track-rails to metallic cross-ties, while providing, at the same time, suitable means to permit of expansion and contraction in the lengths of the rails under changes of atmospheric temperature. This object is attained by means of the constructions now to be described.

In the accompanying drawings, Figure 1, shows in plan a part of railroad track embodying my invention. Fig. 2 shows in side elevation, enlarged, a vertical section taken at the line z, z' , of Fig. 1. Fig. 3, is a horizontal section, taken through the line y, y' , of Fig. 2. Fig. 4, shows a transverse sectional elevation taken through the line z', z' , of Fig. 2. Fig. 5, is a transverse section, enlarged, taken through the line X, X' , of Figs. 1, 6 and 7. Figs. 6 and 7 are views in plan or parts of railroad tracks, showing modified forms of cross-ties which may be used in carrying out my invention.

In said figures, the several parts are indicated by reference letters, by the aid of which said parts and the invention will now be described as follows:

Referring first to Figs. 1 to 5 inclusive, the track-rails A are composed of two parts a, a' , which parts overlap each other so as to break joints and thus form a practically continuous rail. The contiguous, or meeting, ends of each part-rail are connected by splice-bars B, welded to each of said parts, near said ends, so that each part-rail becomes in effect an integral part of the whole line of such rails. It can be readily seen that the shape of the splice-bars B is such—a curve or bend—that said bars will permit the rails to open and close at the joints under the effects of contraction and expansion due to such extremes of temperature as may occur in any given locality. The metal cross-ties C, on which the two-part rails A rest, are provided on their

under sides, with longitudinal ribs, which secure strength and stiffness with lightness and also serve to firmly implant the ties in the ground or in the ballast which may be employed. The ends of the cross-ties C are forked as shown at the points e, e' , which letters indicate bifurcations or prongs. The rails A cross said bifurcations and each part a, a' of the rails is welded to one prong of each cross-tie, as seen as g, h , Figs. 1 and 4. By means of suitable apparatus, these welding operations can be effected partly in the course of the laying of the track and partly at the works previous to shipment, as may be deemed best.

In Figs. 6 and 7 are shown modified forms of cross-ties which may be used in carrying out my invention. In Fig. 6 the tie J is shown having a portion thereof bent to form the hooked end or bent prong j , the parts a, a' , of the rail being welded to the tie at the points h^2 and g^2 , respectively. If desired, attachment between the rail and tie may be omitted at the points h^2 . In Fig. 7, the tie I is shown having portions thereof bent to form the prongs i, i' , the parts a, a' , of the rail being welded to said prongs at the points h' and g' , respectively. The body of the ties I, J, are substantially similar to the body of the tie C, shown in the other figures. It can be readily seen, sufficient flexibility being given to the prongs or bifurcated ends of the cross-ties, that said ends will yield or flex with the creeping or elongation and shortening of the rails, and thus a rigid and practically continuous, integral, line of track is provided which can expand and contract under varying temperatures, without injury to or disruption of its alignment and also without disturbing the main body of the cross-tie, the bifurcated ends only of said tie yielding to expansive motion. A smooth, strong, durable track and road bed are thus provided, which insure easy motion to the cars, comfort to passengers thereon, and reduced wear and tear to car-wheels and running-gear.

I do not confine myself to the shapes of bifurcations and bent prongs shown in the ties, the essential point being that the ends of the ties shall be so shaped as to be free to "come and go" without disturbing the central portions of the ties.

Having thus fully described my invention, I claim—

1. A metal cross-tie, the ends of said cross-tie being flexible or elastic and the tie intermediate to said ends.
2. A metal cross tie formed of a single piece of metal, the ends of said tie being a bent flexible prong or prongs.
3. A metal cross tie having flexible and elastic bifurcated ends.
4. The combination of a two-part-rail and a metallic cross-tie, each of the parts of said rail being welded to said cross-tie.
5. A two-part-rail having its parts welded to different members of a metal cross-tie, said members of the tie being expandible lengthwise of the track.
6. A two-part-rail, having its parts welded to different members of a metal cross-tie, said members of the cross-tie being flexible or elastic lengthwise of the rail.
7. The combination of a two-part rail having broken joints and a metallic cross-tie, the two parts of said rail being welded to said cross-tie.
8. The combination of a two-part-rail and a metallic cross-tie having a prong or prongs at its ends, each of the parts of said rail being secured to one of the prongs of said tie.
9. The combination with railroad rails and

flexible expansion and contraction pieces secured at their ends, of a metallic cross-tie having at its ends flexible extensions on which the rails rest, said tie being connected to the rails.

10. The combination of a metallic cross-tie having a flexible prong or prongs at its ends; rails secured to said ends; and flexible expansion and contraction pieces secured at the ends of said rails.

11. The combination of a metallic cross-tie having a prong or prongs at its ends; a two-part-rail having each of its parts secured to one of said prongs; and a flexible expansion and contraction piece secured at the ends of one part of said rail.

12. A railroad track consisting of the following named elements in combination: metallic cross-ties each having a prong or prongs at its ends; two parallel rails, each constructed of two parts and having each of said parts welded to different prongs of the ends of said ties; and flexible expansion and contraction pieces welded at the contiguous ends of said rails.
